UNITED STATES PATENT OFFICE.

JOHN L. GILL, JR., OF PHILADELPHIA, PENNSYLVANIA.

STEAM-BOILER FURNACE.

SPECIFICATION forming part of Letters Patent No. 408,098, dated July 30, 1889.

Application filed October 3, 1888. Serial No. 287,085. (No model.)

To all whom it may concern:

Be it known that I, JOHN L. GILL, Jr., a citizen of the United States, residing at Philadelphia, in the county of Philadelphia and 5 State of Pennsylvania, have invented certain new and useful Improvements in Flues for Distributing Draft Effect to Steam-Boilers Having One Chimney in Common; and I do hereby declare the following to be a sufficiently full, clear, and exact description thereof as to enable others skilled in the art to make and use said invention.

This invention relates to flues for discharging products of combustion from several nests 15 of boilers, and has for its object the equal distribution and regulation of draft effect upon each boiler without affecting the draft of others and the facility of alternately discharging the products of combustion either 20 directly into the atmosphere or through a water-heating apparatus known as an "economizer."

While there are shown in the drawings other novel features besides these herein 25 claimed, those which are properly a part of the construction and arrangement of boiler-houses are herein shown only to better illustrate this invention, but are the subject of the claims of another application for Letters 30 Patent filed October 3, 1888, and serially numbered 287,084.

To effect these desiderata, this invention consists of the arrangement and combination 35 of flues with passages for access thereto, chimneys, and dampers, hereinafter described, and shown in the accompanying drawings, in which—

Figure 1 shows a transverse vertical section of a three-story boiler-house and steam- 40 generating plant embodying this invention, and Fig. 2 is a rear view vertical section of a boiler-plant in the same boiler-house. The same reference-marks indicate like parts in both figures.

45 A', A², A³, and A⁴ represent boilers or steam-generators resting on the ground-floor, and may be either water-tube boilers or return-tubulars. B', B², B³, and B⁴ are steam-generators in similar settings on the second floor.

50 C' and C² are nests of economizers on the third floor.

D is a chimney, which may be made of

metal throughout or masonry throughout, but preferably in brick or masonry extending above the roof-line of the building, and there 55 may be contracted and supplemented by a cylindrical metallic stack D'.

D' is the extension of the chimney above the roof, which may be made of metal or masonry.

60 D² are vertical divisions of the flues E' E² E³ E⁴ and F', F², F³, and F⁴, which are desirable but not essential.

D³ is a partition-wall which extends centrally from the bottom of the chimney to a 65 point above the level of the second-story battery of boilers, or, in the case of the economizers being used, to a point above the level of the upper part of the economizers C' and C².

E', E², E³, and E⁴ are flues leading laterally from the furnaces A', A², A³, and A⁴ to the base of the stack D, which is expanded at the point of the intersection of the flues F', F², F³, and F⁴, so that at this point the 70 chimney is equal in cross-sectional area to the several flues E', E², E³, and E⁴ and F', F², F³, and F⁴.

Beneath the flues E', E², E³, and E⁴ and F', 75 F², F³, and F⁴, and between the rear of the boiler-settings and the outer wall of the building, are passage-ways R and R' for access to the rear of the boilers and flues through doors (marked S and S') opening from said 80 passages R and R' into the rear of the boiler furnaces or settings.

85 G G are lateral flues for conducting the heat and waste gases from the chimney to the rear end of the economizers.

G' G' are openings in the stack, through which the gases pass into the flues G G.

90 H H are dampers, which close the openings G' when in a vertical position and allow the products of combustion to directly ascend the stack D, or when in a cross position close the stack above the opening G', so as to turn the 95 gases into the flues G G. By the arrangement shown each boiler-furnace delivers its products of combustion through a lateral flue into the chimney D in the direction of the draft of the chimney.

100 The partition D³ prevents the upward current of the gases from being broken by meeting volumes of cooler and unexpanded air or gas, and in combination with the damper H

the products of combustion are directed into the economizer (when one is used) in the manner shown, avoiding all descending drafts. Thus the products of combustion are directed and conveyed from each furnace without risk of interference from the operation of any of the other furnaces.

Having described this invention and the operation thereof, what I claim is—

- 10 1. In steam-boiler furnaces, the combination of the chimney D, having a partition D³, dividing the same to a point above the highest boiler-setting, with lateral flues leading from each furnace and terminating in a vertical flue in the chimney D, substantially as set forth and shown.
- 15 2. In steam-boiler furnaces, the chimney D, in combination with lateral flues E' E² and

F' and F², terminating vertically in the chimney D, with the economizer C', located above 20 the boiler-furnaces and provided with a damper H, arranged to alternately direct the products of combustion through the economizer in one adjustment or to discharge them directly through the chimney, substantially 25 as shown and described.

3. In steam-boiler furnaces, the combination of a series of lateral flues E' E² E³ E⁴ and F', F², F³, and F⁴ with the passage-ways R and R' under said flues for access to the rear of 30 the boiler tubes and settings, arranged substantially as shown and described.

JOHN L. GILL, JR.
